UNITED STATES PATENT OFFICE.

WILLIAM H. PHILPOT AND RUDOLPH VERTISKA, OF HUMBOLDT, NEBRASKA.

FLOOR.

1,018,987.

Specification of Letters Patent.

Patented Feb. 27, 1912.

Application filed April 2, 1909. Serial No. 487,448.

To all whom it may concern:

Be it known that we, WILLIAM H. PHILPOT and RUDOLPH VERTISKA, citizens of the United States, residing at Humboldt, in the county of Richardson and State of Nebraska, have invented new and useful Improvements in Floors, of which the following is a specification.

This invention relates to improvement in floors, especially as used for the bottoms of wagon beds, grain cars, platforms, and in ware-houses and on which shoveling is done in handling commodities in bulk, the object of the invention being to combine with the flooring boards, which have grooves in their opposing edges, wear-strips of metal disposed between the opposing edges of the flooring boards, extending to and flush with the upper and lower surfaces thereof and provided at points between their upper and lower edges with laterally extending tongues which engage the grooves in the flooring boards, the said wear-strips serving to prevent wear of the flooring boards and presenting metal surfaces between the flooring boards which greatly facilitate the use of the shovel on the floor, as hereinafter described and claimed.

In the accompanying drawings:—Figure 1 is a perspective, partly in section, of a portion of a floor provided with wear-strips constructed and disposed in accordance with this invention. Fig. 2 is a detail perspective view of one of the wear-strips. Fig. 3 is a cross-sectional view of the same, on a larger scale.

In accordance with this invention, the flooring boards 1 are provided in their opposing edges with grooves 2. Between each pair of flooring boards is placed a wear-strip 3, which is preferably made of iron or steel, and the upper and lower edges of

which are flush with the upper and lower surfaces of the flooring boards. Each of the said strips is provided at opposite sides at points midway between the upper and lower edges with laterally extending tongues 4 formed integrally therewith, which tongues engage and fill the grooves 2 of the flooring boards and serve to firmly connect the wear-strips of the flooring boards. The outer edges of the wear-strips are rounded, as at 5, at the exposed surfaces of the flooring boards.

It will be understood that the wear-strips present metallic upper surfaces at the upper surfaces of the floor which serve to prevent the flooring boards from being worn by the scraping of a shovel when material is being shoveled from the floor. Furthermore the said metallic upper surfaces of the wear-strips in addition to preserving the floor, also facilitate the movement of the shovel on the surface of the floor.

Having thus described the invention, what is claimed is:—

As a new article of manufacture, a cross-shape strengthening spline for mill floors, said spline being constructed to have a comparatively thin longitudinal vertical web the top and bottom edges of which are adapted to extend flush with the upper and lower faces of the floor planks and central oppositely disposed horizontal longitudinal side tongues adapted to enter central longitudinal grooves in the edges of the floor planks of a mill floor.

In testimony whereof we affix our signatures in presence of two witnesses.

WILLIAM H. PHILPOT.
RUDOLPH VERTISKA.
